FLOATING DOOR BOTTOM SEALING DEVICE

Kurt Oliver Pietrushak, Lima, Ohio

Application November 17, 1949, Serial No. 127,810

1 Claim. (Cl. 20—68)

1

This invention relates to an automatic sealing device for swinging doors, and an object is to produce a new and improved device which can be applied to doors for automatically sealing the space between the bottom edge of the door and the sill when the door is closed.

Another object is to provide a door with a simple and efficient sealing device for sealing the space between the bottom edge of the door and the sill when the door is closed, the rail or bar effecting the automatic sealing action being of relatively hard metal and the sill being of softer metal so that the sealing bar will automatically form its own sealing groove for more effectively establishing the desired sealing contact between these parts.

Other objects reside in details of construction, arrangement and assembly, and for purposes of illustration but not of limitation, an embodiment of the invention is shown in the accompanying drawings, in which

Figure 1 is a fragmentary side elevation of a door frame, a swinging door mounted within the frame and equipped with an automatic sealing device for sealing the space between the bottom edge of the door and the sill;

Figure 2 is an enlarged fragmentary side elevation of the automatic sealing device and sill, a part being broken away to show one of the springs and the manner in which it is mounted;

Figure 3 is a fragmentary perspective view of the rail or bar which effects the seal;

Figure 4 is a transverse sectional view substantially on the line 4—4 of Figure 2; and

Figure 5 is a transverse sectional view on the line 5—5 of Figure 2.

The illustrated embodiment of the invention comprises a door frame F, the opening of which is adapted to be closed by a hingedly mounted door D. The sill 10 extends across the threshold of the door and as indicated in Figure 4, it has downwardly sloping sides 11 and a horizontally extending flat top portion 12. Preferably, the sill 10 is of relatively soft metal such as aluminum or brass.

Formed at the bottom edge of the door D, midway between the sides and extending from side to side, is a socket 13 which is open at the lower end and which is substantially rectangular in cross section. Manifestly, the formation of the socket 13 provides tenon-like portions 14 and 15. Embracing the tenon-like extensions 14 and 15 are sheet metal shields 16 and 17 respectively, each shield being substantially U-shaped in cross

2

section but having a shorter side which extends to the inner end of the socket 13 and a longer wall on the adjacent side of the door. These shields are important in affording adequate strength and rigidity to the lower edge portion of the door and militate against splitting of the wood of the door and insure the proper and satisfactory action of the sealing member, as will hereinafter appear.

10 Mounted within the socket 13 and extending substantially from side to side of the door D is a rail or bar 18 which is rectangular in cross section and is preferably of a relatively hard metal such as steel. The lower end of the bar 18 is flat to engage the sill 10 and to ride over one of the sloping faces 11 thereof, but normally rests when the door is in closed position, against the top flat surface 12 of the sill.

20 Formed in the bottom of the socket 13 are a series of sockets 19 and in registry with sockets 20 formed in the upper portion of the rail 18. Disposed in the registering sockets 19 and 20 are coil springs 21 respectively which urge the lower edge of the bar 18 into engagement with the sill 10. 25 The force of these springs 21 is so chosen as to effect a good seal with the threshold and since the rail is of a hard metal, such as steel, and the sill or threshold is of a softer metal, the rail will form or create its own seat in the top surface 12 of the sill. This also is of advantage in the event of inaccuracy in the positioning of the parts and thereby compensates for such irregularities.

30 To retain the bar 18 on the door and to limit its outward movement, a series of rivets 23 extend through the shields 16 and 17 and through vertically elongate holes 24 formed in the bar 18. The rivets 23 also serve to retain the shields in the desired position on the door.

40 It is to be understood that numerous changes in details of construction, arrangement and assembly may be effected without departing from the spirit of the invention especially as defined in the appended claim.

45 What I claim is:

A device of the class described for installation on a door having an elongate rectangular socket extending substantially throughout the length of the bottom edge thereof, said device comprising 50 a pair of elongate sheet metal shields, each being U-shaped in cross section for embracing the lower edge of the door with portions on the inside and outside of the door respectively, a solid metallic bar rectangular in cross section normally projecting from said socket and vertically movable

therein and in sliding engagement with the adjacent sides of said shields respectively, said bar having a series of sockets in the upper edge portion spaced from each other, helical coil springs in said sockets for urging the bar in a direction toward the bottom edge of the door, a series of laterally spaced vertically elongate slots in said bar, and rivets extending through said shields and through said slots respectively for limiting the vertical movement of said bar.
